UNITED STATES PATENT OFFICE.

MITRIDATES H. PLATA, OF NEW YORK, N. Y.

SALIVA-EJECTOR.

Serial No. 1,147,341.

Application filed November 30, 1914. Serial No. 874,727.

Specification of Letters Patent. Patented July 20, 1915.

To all whom it may concern:

Be it known that I, MITRIDATES H. PLATA, a citizen of Peru, residing at New York, in the county and State of New York, have invented a new and useful Saliva-Ejector, of which the following is a specification.

This invention relates to ejectors used specially for the removal of saliva from the mouth of a patient during dental operations; and the object of the invention is to provide a device of this character so cheap to manufacture that when once used it may be discarded and a new one used on the next patient.

A further object of my invention is to provide a device of this kind which can be used with the minimum of discomfort.

The invention is illustrated in the accompanying drawing, in which—

Figure 1, is a side view of a saliva ejector constructed in accordance with my invention with a portion of the connecting rubber tube attached; Fig. 2 is a top plan view of the ejector; Fig. 3, is a sectional view, on an enlarged scale, on the line 3—3 of Fig. 1; Fig. 4, is a side view of the mouth-engaging end of the ejector, showing a modified form of construction; and Fig. 5, is a sectional view, on a slightly enlarged scale, on the line 5—5 of Fig. 4.

In the drawing similar numerals of reference refer to the same parts in each of the views.

In practice I provide a saliva ejector preferably made of prepared paper, or similar material, so that it can be manufactured cheaply, and when once used can be thrown away so that a new one will be supplied for the next patient.

As shown in the drawing, the ejector consists of a tube 6, formed from prepared paper spirally wound, the separate spirals being indicated by 7. The tube is bent at 8, to form a U-shaped portion whereby a part 9, is provided for insertion in a patient's mouth. In practice it is desirable to partially close the mouth-engaging end, for reasons hereinafter explained, and to provide an enlarged portion, or end, with side ports.

This I accomplish by providing a bulb 10, which is preferably fixed in the end of the tube 6; and this bulb is provided with a side port 11, on each side. The long end 12, of the ejector may be mounted in a rubber

tube 13, the end of which may be placed in 55 the water running through a basin.

In operation, when dental work is to be done, the end 9, of the ejector is inserted in the patient's mouth, and the free end of the rubber tube 13, is placed in the running wa- 60 ter. As saliva is formed in the mouth of the patient, the suction caused in the ejector by the running water will cause the saliva to enter, and pass through the ejector to be dis- 65 charged without inconvenience to the pa- tient or dentist.

As the running water will cause considerable suction through the ejector, if the end entering the mouth were left open the light inner lining of the mouth would likely be 70 drawn into the end of the tube thereby stop- ping the passageway through the same. To prevent this the bulb 10, is provided which is of sufficient size to slightly expand the surrounding portions, and a plurality of 75 ports are provided so that under no circum- stances will all be stopped up by the lining, and the ejector will thus always be kept in an operative condition.

It is common to make tubes out of paper 80 either spirally wound, or with edges fixed together; but in this application I show one of these tubes bent into a particular shape for a particular purpose. Further, while it is not so difficult to make a tube of paper, it 85 is difficult to make a tube with an enlarged, closed end. By making a bulb with side ports, and fixing the same in the end of the paper tube the problem of manufacturing is greatly simplified, and a very efficient ejec- 90 tor is provided.

As the part 9, must enter the mouth of the patient, it is desirable owing to its fragile nature that it separate the lips, and es- 95 pecially the teeth as little as possible. In some cases the patient may nearly close the teeth and the ejector might be permanently injured. Then, too, as the teeth present a substantially flat surface, by providing the ejector with a corresponding flat surface the 100 ejector will rest in the mouth of the patient in a more firm manner. To provide for this, I flatten the tube 6, at 14, whereby a flat bottom 15, and a flat top 16, is provided. This widens the channel 17, through the 105 tube 6, but does not reduce the area of the same, as will be clear.

In Figs. 4, and 5, the parts 6', 7', 8', 9',

10', 11', and 12', are the same as in Figs. 1, 2, and 3; but the tube at 14', is flattened on the bottom only, as shown at 15'. This will insure the ejector resting firmly on the teeth of the patient, and may be used instead of the construction shown in Figs. 1, 2, and 3.

In manufacture, the tube 3, can be formed out of prepared paper, or other suitable material, in a manner well known, and may be 10 bent, or formed in to the desired shape. The bulb 10, may be previously formed, or formed at the time it is inserted, or fixed in the end of the tube 6.

The entire construction is such that it will 15 be cheap to manufacture; will be effective in use; and will be perfectly sanitary as a new ejector will be used for each patient.

I claim:

1. A saliva ejector formed of prepared 20 paper U-shaped in form, one end of said ejector carrying a closed end with a port in the side thereof.

2. A saliva ejector formed of prepared paper spirally wound and U-shaped in form,

one end of said ejector carrying an enlarged 25 and closed end with a plurality of ports in the side thereof.

3. A saliva ejector comprising a tube formed from paper U-shaped in form, and a bulb closing one end thereof, said bulb being provided with a plurality of perforations which communicate with the interior of said tube. 30

4. A saliva ejector having a U-shaped portion made of paper with the inner intermediate portion flat, for the purpose set 35 forth.

5. A saliva ejector comprising a tube formed from prepared paper U-shaped in form with the intermediate portion flattened, and a bulb fixed in one end of said tube, said bulb being provided with a plurality of perforations which communicate with the interior 40 of the tube, for the purpose set forth.

Dated this 20th day of November, 1914.

MITRIDATES H. PLATA.
